UNITED STATES PATENT OFFICE.

SAMUEL MAWHINNEY, OF WORCESTER, MASSACHUSETTS, ASSIGNOR OF
ONE-HALF TO ROBERT L. GOLBERT, OF SAME PLACE.

BOOT OR SHOE TREE.

SPECIFICATION forming part of Letters Patent No. 374,311, dated December 6, 1887.

Application filed June 13, 1887. Serial No. 241,126. (No model.)

To all whom it may concern:

Be it known that I, SAMUEL MAWHINNEY, a citizen of the United States, residing at Worcester, in the county of Worcester and State of Massachusetts, have invented certain new and useful Improvements in Boot or Shoe Trees, of which the following, together with the accompanying drawings, is a specification sufficiently full, clear, and exact to enable persons skilled in the art to which this invention appertains to make and use the same.

The object of my present invention is to provide a treeing apparatus for boots and shoes, wherein the foot is provided with laterally-adjusting side pieces and expanding devices that are automatically brought into action for spreading the foot when it is placed on the body or leg of the tree and relieved to permit the contraction of the foot when it is removed therefrom.

Another object is to provide a tree having a removable heel-seat piece adapted to slide onto and off from the end of the standard, in the manner hereinafter explained, to facilitate changing for different sizes and shapes of boots or shoes.

Another object is to improve the construction of the tree in various parts and details, as hereinafter more fully described, to render the mechanism more efficient and convenient for use.

The special features of my invention and the particular subject-matter claimed are herein-after definitely specified.

In the drawings, Figure 1 is a side view of a boot-tree constructed in accordance with my invention. Fig. 2 is a longitudinal section of the same. Fig. 2^a is a similar section of some of the parts, showing the foot-latch in depressed position. Fig. 3 is a top view of the leg-frame with the front removed and the heel-seat piece separate from the leg-frame. Fig. 4 is a transverse section at the position of line x x, Fig. 2. Fig. 5 shows details of the latch-lever. Fig. 6 is a bottom view of the tree, showing the foot expanded. Fig. 7 is a bottom view of the foot with the sides contracted. Fig. 8 is a side view of the foot with one of the adjustable sole-pieces removed to show the expanding devices. Fig. 8^a shows a side view

of the foot-iron, made with a half-way notch. Fig. 9 is a sectional view of the foot at the position of line y y, Fig. 8; and Fig. 10 illustrates a modification of the expanding devices.

Referring to parts, A denotes the leg-frame or metal body having a cylindrical head or journal, A', whereby the tree is supported in connection with the bench and jacking devices, which may be of the ordinary well-known construction.

B indicates the back piece arranged between the side brasses or plates, a, which are screwed to the sides of the leg-frame. The back B is adjustably confined by the nut b', in connection with the threaded stud A², and provided with inclined guideways at b, that engage with the inclines on the head C' of the straining-rod C, for operation in the usual manner. The front piece, a', of the leg may be of ordinary construction and form, as heretofore employed in boot or shoe trees, and may be rigidly attached to or made integral with the leg-frame.

D indicates the foot-piece, which I provide with laterally-movable sides or sole-pieces D', that are connected to the main part of the foot by the pivot-studs e, which pass through the forward ends of said sole-pieces, while their rear ends are free to be moved in and out laterally. The rear ends of said sole-pieces are confined in proper relation to the foot by an overhanging portion thereof, as at d, or in other equivalentsuitable manner. The joint between the main part of the foot and movable sides D' is preferably made straight, or as a plane inclined to the plane of the rear seating-surface, and a metal plate, d', is attached to the foot to give strength thereto and to form a good bearing-surface for the side pieces, D'.

Between the movable sides D', and mounted in bearings connected with the main part of the foot, is an expander or rod, F, carrying right and left inclined guideways f, that engage or interlock with lugs or grooved bearing-plates f² on the inner portion of the adjustable parts D'. The end of the rod F is projected through the rear end of the foot, as indicated at F' in Figs. 7 and 8.

A spring, G, is provided for pressing back the rod F for contracting the foot at the ball,

by drawing together the rear ends of the sole-pieces D. When the rod is forced forward or toward the toe, the sides D' are spread apart by the action of the inclines, thus expanding the foot. A guide, d³, is provided for supporting the rod F at a central position and preventing displacement by side pressures. The parts D' may be cut away internally to give space for the expanding devices, as required.

The foot-iron H, which is fixed to the rear end of the foot, is made dovetailed or beveled at the sides, and fitted to slide into a correspondingly-shaped groove on the leg-frame.

15 Said iron terminates at a position adjacent to the position where the rod F projects from the rear of the foot-piece, so that the latching mechanism will act on both the foot-iron I and the bar F, as hereinafter explained.

20 The leg-frame or body is provided with an inclined surface or lug, m, that engages the end of the bar F when the foot is pressed onto the tree, and forces said bar F toward the toe for expanding the foot.

25 A latch bar or lever, I, is pivoted within the leg or frame at i, and is provided with a lug at its rear end, that engages the foot-iron H for retaining the foot in connection with the leg. Said latch-lever is actuated for effecting engagement and disengagement of the foot by

30 means of an extension on the end of the straining-rod C, which is provided with a ball or lug, e, that passes under the end of the latch-lever when the pull-rod starts backward, (see Fig. 2,) and forces the latch upward past the angle of the foot-iron, and also

35 against the end of the bar F. When raised, the straight surface of the latch-bar permits the lug e to be moved along beneath it to any 40 distance without further affecting the action thereof. When at its extreme forward limit, the lug e passes beyond the end of the latch-bar, and thus allows the latter to drop away from the foot-iron, and thus release the foot, 45 (see Fig. 2^a), so that it can be taken off.

The automatic lateral expansion of the foot by devices brought into action when placing the foot on the tree, or by the action of the tree-straining devices, is a feature of my in-

50 vention.

The foot-iron may be made either straight on its under side, as in Fig. 8, or with an offset or notch, h, as in Fig. 8^a, the former construction being that best adapted for use when 55 treeing long-legged boots, for which the foot D requires to be detached or taken completely off from the body or leg-frame and inserted in the boot before it is put onto the tree, and the latter form is adapted for use when treeing low-topped boots or shoes, wherein it is 60 desired to simply draw the foot-piece partially off without entirely disengaging it from the body of the tree when taking off and putting on the work. In this latter instance the off- 65 set or notch h serves as a convenient half-way notch or stop for the foot as it is drawn outward to avoid the slipping of the foot too far.

When employed in a shoe-tree, or with the foot-iron having the notch h, the lever I is best made with a weighted or counterbalancing end, 70 I', as indicated by dotted line, Fig. 2, and as in Fig. 5; but for boot-work, wherein the foot requires to be taken off from the leg at each operation, said latch is best made without said counterweighting end, or is cut off just back 75 of the pivot-center i, as at line w on Fig. 5.

K indicates a detachable heel-seat block, which includes the two sides from the bottom of the foot to the ankle, and is fitted to slide on and off from the end of the leg-frame, in 80 the manner illustrated, for effecting interchanges for different sizes and shapes. Said heel-seat is made with a web or plate, K', connecting its two sides, and with overhanging lips l, that interlock with corresponding grooves, 85 l', on the reduced end K² of the leg-frame. The exterior of the part K² and the interior of the part K are preferably slightly tapered, so that they will make a close fit when the end of the part K abuts against the leg at the ankle-joint 90 J. The heel-seat K is slipped off and onto the part K² of the leg by endwise movement, and forms a solid body therewith when in position thereon. Portions of the side plates or brasses, a³, are attached to the heel-seat block 95 K, and go with the same when the interchange of the parts K is effected.

P indicates the spring for pressing the straining-rod toward its normal position in opposition to the action of the jacking devices. Said 100 spring is disposed about the rod C within the leg in the usual manner.

In the operation, when the foot D is removed from the leg B, the side pieces, D', collapse or come together, as in Fig. 7, so that the foot 105 can readily be inserted into or withdrawn from the boot. When placed in the boot and the boot put onto the leg A, the end of rod F strikes the inclined surface m, and is thereby forced upward as the foot is pressed forward 110 to place, partially expanding the sides. Then when the latch I is forced up by the action of the straining-rod, the end I' of the latch, acting on the end of the bar F, forces said side pieces, D', still farther apart, causing the foot 115 to fill the boot in a full and complete manner.

In Fig. 10 I have shown a modification of the boot-expanding devices, wherein links f⁴ are used in lieu of inclined lugs for pressing outward the side pieces, D'. Other means may 120 be employed for forcing apart the side pieces, if preferred—as, for instance, the side pieces may be extended, as per dotted lines D⁴ on Fig. 7, so that said ends will engage with a wedge or double-inclined end on the frame, latch, or 125 straining-rod when the foot is placed on the leg.

What I claim as of my invention, and desire to secure by Letters Patent, is—

1. In a boot or shoe tree, a removable foot having the movable sides pivoted at or near the toe and swinging laterally at their rear ends, in combination with an expanding device, substantially as described, adapted for pressing 130

apart the sides laterally at their rear ends when the foot is placed upon the leg portion of the tree.

2. In a boot or shoe tree, the combination of 5 a foot-piece having movable sides adapted to expand and contract the foot laterally, in combination with expanding mechanism, substantially as described, actuated by the locking device, whereby the foot is held to the leg of the 10 tree, substantially as set forth.

3. In a boot or shoe tree, the combination, with the foot having the expansible or movable sides, of the reciprocating spindle provided with inclined guides that work in conjunction 15 with inclined guides or lugs on said movable side pieces, the retracting-spring, and a lug or device which engages said spindle and presses it forward when the foot is applied to the leg portion of the tree.

20 4. In a boot or shoe tree, the combination of the foot having the laterally-movable sides D', and the adjusting-bar F for effecting their lateral movement connected therewith, and having its end projecting at the seating end of said 25 foot, and the incline m for engaging and actuating said bar, substantially as set forth.

5. In a boot or shoe tree, the foot-piece having a dovetailed foot-iron on its seating end, said foot-iron terminating with its outer end at 30 a short distance back from the sole of the foot-piece, in combination with the leg-frame having a foot-seating surface and guiding-grooves to receive said foot-iron and a latch device or hook that locks over the outer end of said foot-iron when the foot is at normal position on the 35 leg, substantially as and for the purpose set forth.

6. In a boot or shoe tree, the combination of the foot having the iron H, the latch I, the 40 straining-rod C, provided with the extension or lug e, and the leg-frame A, having guides for said foot-iron and extension, substantially as set forth.

7. In a boot or shoe tree, the foot having the 45 movable sides D', expanding-bar F, and foot-iron H, in combination with the latch-bar I, pivoted within the leg at i and furnished with a lug that engages said foot-iron and expanding-bar, substantially as and for the purpose set forth.

50 8. In a boot or shoe tree, the foot-iron H, provided with the notch h, in combination with the

foot D, the leg-frame A, and the latch I, substantially as and for the purpose set forth.

9. The combination, with the foot provided with the foot-iron having notch h, of the latch-lever provided with the counter-balance or weighted end, substantially as and for the purpose set forth. 55

10. In a boot or shoe tree, the detachable heel-seat piece K, consisting of the sides and 60 sections of the side brasses, a³, connected by a web, K², and extending from the sole to the ankle-joint j, in combination with the foot, and the leg-frame having a reduced end, onto and from which said heel-seat can be adjusted, substantially as and for the purpose set forth. 65

11. In a boot or shoe tree, the combination of the foot having the foot-iron H and laterally-adjustable sides or sole-pieces D', the expanding-bar F, provided with devices for moving 70 said side pieces, the leg-frame having the incline or lug m, the latch-bar I, and the straining-rod C, having the extension end provided with boss c, substantially as and for the purpose set forth. 75

12. The combination, with the main part of the foot D and the laterally-adjustable sides D', of a reciprocating rod or operator disposed between said side pieces and connected therewith for effecting their lateral movement, and a 80 guide, f, fixed on the main part of the foot, confining said operator and adjustable sides against displacement by side pressure, substantially as set forth.

13. In a boot or shoe tree, the combination, 85 substantially as described, of the back piece, B, having inclined guides b, the straining-rod having a head that engages therewith, the leg-frame A, having guideways for said rod-head, the detachable foot fitted to said leg-frame with 90 a dovetailed foot-iron, the latch-bar pivoted in said leg-frame and engaging said foot-iron at its rear end, and a latch-actuating device connected with said straining-rod and brought into action by the same movement that throws 95 out the back piece, substantially as set forth.

Witness my hand this 11th day of June, A. D. 1887.

SAMUEL MAWHINNEY.
